UNITED STATES PATENT OFFICE.

JOSEPH O. HOLLIS, OF BOSTON, MASSACHUSETTS.

DESIGN FOR DOOR-KNOBS.

Specification forming part of Design No. 6,956, dated October 14, 1873; application filed October 2, 1873.
[Term of Patent 3½ years.]

To all whom it may concern:

Be it known that I, JOSEPH O. HOLLIS, of Boston, in the county of Suffolk and State of Massachusetts, have invented a Design for Door-Knobs, of which the following is a specification:

This design is upon the shanks of a door-knob; and in the drawings the design is shown by a side view of the knob.

A is a door-knob, to which B is the shank. This shank from end to end is of the outline shown in the drawings. Midway between the rose-plate C and the knob A, and for a portion of the length of the shank, the outline is cylindrical, as at a, and each side of such cylindrical portion a the outline is in a two-part concave, b and c, each part of larger diameter than the cylindrical portion a. The one con-

cave part, b, makes a shoulder, d, at the cylindrical portion a, and it intersects the other concave part, c, leaving an edge, f. In each case the concave part c completes the length of the shanks, as shown.

Having thus described my invention, what I claim, and desire to secure by Letters Patent, is—

The design for the shank of a door-knob, herein shown and described.

The above specification of my improved design for door-knobs signed by me this 15th day of September, A. D. 1873.

J. O. HOLLIS.
